UNITED STATES PATENT OFFICE.

RUDOLPH KOTKAS, OF PORTLAND, OREGON.

CIRCUIT-CLOSER DEVICE.

1,280,242.

Specification of Letters Patent.

Patented Oct. 1, 1918.

Application filed November 20, 1917. Serial No. 203,020.

To all whom it may concern:

Be it known that I, RUDOLPH KOTKAS, a citizen of the United States of America, residing at Portland, State of Oregon, have 5 invented certain new and useful Improvements in Circuit-Closer Devices, of which the following is a specification, reference being had therein to the accompanying drawing.

10 This invention relates to a burglar alarm and has for its object the production of a simple and efficient means for causing an alarm to be sounded should a person step upon the floor under which the alarm is 15 placed.

Another object of this invention is the production of a simple and efficient circuit closing means used in connection with the alarm.

20 With these and other objects in view this invention consists of certain novel constructions, combinations and arrangements of parts as will be hereinafter fully described and claimed.

25 In the drawings:—

Figure 1 is a transverse sectional view through a portion of a floor and means for supporting the same showing the circuit closing and alarm means carried thereby.

30 Fig. 2 is a section taken on line 2—2 of Fig. 1.

Fig. 3 is a section taken on line 3—3 of Fig. 2.

Fig. 4 is a perspective view of the circuit 35 closing lever and gage plate secured thereto.

Fig. 5 is a vertical section through the loop of the gage plate showing the same engaging the lower end of the contact lever.

By referring to the drawings it will be 40 seen that 1 designates the floor which is supported upon the usual main beams or joists 2. One of the joists 2 is provided with a secondary beam or joist 3 spaced from the main beam or joist 2 as shown in Fig. 2 of 45 the drawings. A hanger yoke 4 is secured to the under face of the secondary beam or joist 3 and this hanger yoke 4 supports a contact lever 5. This contact lever 5 is provided with an upturned end 6 having an 50 aperture 7 formed therein through which aperture 7 passes the hanger member 4 for supporting the contact lever or member 5. This contact lever 5 is provided with a rolled upturned end 8 carrying an insulating sleeve 9 through which passes a conducting rod 10, the conducting rod 10 be-

ing provided with an eye 11 at one end and a contact knob 12 at the other end. The eye 11 is connected to one end of a coil spring 13 and the opposite end of this coil 60 spring 13 is anchored in engagement with a binding post 14 carried by the floor 1.

A gage plate 15 is pivotally mounted upon the joist 2 by means of a pivot pin 16 and this gage plate 15 is provided with a rolled portion 17, which rolled portion fits down into a notch 18 formed in the upturned end 6 of the lever 5 for the purpose of swinging the lever 5 as the gage plate 15 is swung thereby swinging the upper end of the lever 70 5 into an adjusted relation with respect to the contact spring 19. The gage plate 15 is provided with a pair of parallel depending fingers 20 which fingers are adapted to fit around a screw 21 which screw 21 supports 75 a thumb nut 22 for threading upon the screw 21 and holding the gage plate 15 in an adjustable position.

A contact spring 19 above mentioned is secured to the beams or joists 2 by means of 80 the binding posts 23, the spring 19 having laterally extending ends 24 as shown in Fig. 3 of the drawings. One of the binding posts 23 is connected to a wire 25 which wire 25 may be provided with a suitable 85 switch 26 to permit the alarm to be thrown off or on according to the will of the operator and thereby permitting the alarm to remain inoperative during certain period of time when it is desired to walk upon the 90 floor without sounding the alarm. The wire 25 is connected to a battery 27 and this battery 27 is connected to a wire 28 the wire 28 being in turn connected to the bell 29. This bell 29 is connected to the binding post 95 14 by means of a wire 30.

From the foregoing description it is to be understood that the spring 13 is but a small copper coil for the purpose of carrying the electric current in order to make the circuit, 100 and also with just enough tension so that when there is no cause for the alarm to act the lever 5 will be pulled back to an open position, thus breaking the circuit. The operation of the device, with gage plate 15 being attached to the joist 2, connected with the end 6 of lever 5, the end 6 being fastened to joist 3, is when a weight is placed upon the floor, causing the joist 2 to bend, joist 3 being apart or separate from joist 2 and attached only at its ends, it does not bend, and, therefore, inasmuch as 105 110

the joist 2 does bend, carrying with it gage plate 15, thus causing a pressure on the inner end of end 6, moving the lever 5 inward, forming a connection between knob 12 and 5 spring 19, completing the circuit and causing the alarm to ring.

What is claimed is:

1. A circuit closer device comprising a beam, a floor supported upon said beam, a contact spring carried by said beam, a contact lever pivotally secured to one side of said beam, a spring secured at one end to the upper end of said lever and at the other end to said floor, and a gage plate secured 15 to the beam and engaging the lever for swinging said lever upon its pivot for adjusting the lever with respect to said contact spring.
2. A circuit closer device comprising a main beam and a secondary beam, a floor above said beam, a contact spring se-

cured to said main beam, a contact lever provided with an up-turned lower end, said end provided with an aperture and with a notch in its upper edge, means extending 25 through the aperture and pivotally mounting said lever upon said secondary beam, a gage provided near one end with depending fingers and at its other end with a rolled portion resting in the notch of the up-turned end of the lever, means pivotally mounting 30 said gage upon said main beam, means engaging the fingers for holding said gage in an adjusted position for controlling the position of the upper end of the contact lever 35 with respect to the contact spring, and yieldable means fastened at one end to the upper end of said contact lever and at its other end to said floor.

In testimony whereof I hereunto affix my 40 signature.

RUDOLPH KOTKAS.
